UNITED STATES PATENT OFFICE.

JOSEPH KOPECKY, OF CAINESVILLE, MISSOURI.

DESIGN FOR A MINER'S CANTEEN.

44,371.

Specification for Design.

Patented July 22, 1913.

Application filed January 13, 1913. Serial No. 741,887. Term of patent 14 years.

To all whom it may concern:

Be it known that I, JOSEPH KOPECKY, a citizen of the United States, residing at Cainesville, in the county of Harrison and State of Missouri, have invented a new, original, and ornamental Design for Miners' Canteens, of which the following is a specification, reference being had to the accompanying drawing, forming a part thereof.

In the drawing, Figure 1 is a perspective view looking at the front portion of the can-

teen, and Fig. 2 is a perspective view looking at the canteen from the rear.

I claim:

The ornamental design for a miner's canteen, as shown.

In testimony whereof I affix my signature, in the presence of two witnesses.

JOSEPH KOPECKY.
